(57) **CLAIM**

We claim the ornamental design for a display screen or portion thereof with animated graphical user interface, as shown and described.

DESCRIPTION

FIG. 1 is a first image in a sequence for a display screen or portion thereof with animated graphical user interface showing our new design;

FIG. 2 is the second image thereof;

FIG. 3 is the third image thereof;

FIG. 4 is the fourth image thereof;

FIG. 5 is the fifth image thereof;

FIG. 6 is the sixth image thereof;

FIG. 7 is the seventh image thereof;

FIG. 8 is the eighth image thereof; and,

FIG. 9 is the ninth image thereof.

The evenly spaced broken lines illustrate portions of the graphical user interface. The dot-dot-dash broken lines illustrate a display screen or portion thereof. The dot-dash broken lines illustrate a boundary line. None of the broken lines form part of the claimed design.

The appearance of the animated user interface sequentially transitions between the images shown in FIGS. 1-9. The process or period in which one image transitions to another forms no part of the claimed design.
